UNITED STATES PATENT OFFICE

JAMES CUTHILL, OF BRAMHALL, ENGLAND, ASSIGNOR TO THE OIL WELL ENGINEERING COMPANY LIMITED, OF STOCKPORT, ENGLAND

WELL DRILLING APPARATUS

Application filed December 28, 1931, Serial No. 583,486, and in Great Britain September 30, 1931.

This invention relates to apparatus for drilling deep wells for oil, water and the like, by the rotary method wherein the drilling tool is carried to the bottom of the 5 hole on a drill pipe rotated at ground level by means of an appliance known as a rotary table, through which passes a hollow drill stem connected to the said pipe and suspended in the derrick by means of a swivel 10 connected to hoisting tackle, means being provided whereby mud or other liquid flush is forced through the swivel, drill stem and drill pipe to the tool for washing the cuttings to the surface.

15 In apparatus of the above class it is usual to operate the hoisting tackle from a type of winch known as a drawworks, provided with a drum having heavy brakes, by means of which the gradual downward feed of the 20 tool is controlled as it drills the hole. This method of applying the feed to the drill is subject to serious disadvantages owing to the fact that it depends entirely on the care and skill of the operator manipulating the brakes 25 on the drum of the drawworks, and very serious troubles have occurred in the use of these brakes and in failure of the braking equipment under the very heavy loads which are customary in this method of drilling.

30 Methods have been devised to circumvent these troubles, one method being to apply an automatic feed to the mechanism of the drawworks; another is to arrange hydraulic feeding cylinders incorporated in the design of 35 the rotary table. Both these methods, however, involve costly and complicated apparatus, and it is accordingly one of the objects of the present invention to provide a simple apparatus which may be applied as an adjunct or accessory to the standard types of 40 drilling equipment and by means of which a positive and safe feed control is provided.

Another object is to provide a means 45 whereby gravity may be supplemented by a downward force applied to the drill pipe and to the drill tool when required.

A further object is to enable a direct indication to be obtained of the suspended weight 50 of the drilling string and by inference the

weight or pressure being applied to the drilling tool at the bottom of the hole.

Other and further objects and advantages attained by the invention will be pointed out hereinafter or will be apparent to one skilled 55 in the art upon an understanding of the invention or its employment in practice.

In the accompanying drawings forming a part of this specification I show one structural arrangement in which the invention 60 may be embodied, but it is to be understood that this is presented for the purpose of illustration only and is not to be accorded any interpretation having the effect of restricting the claims short of the true and most 65 comprehensive scope of the invention in the art.

In the drawings:—

Figure 1 is an elevation of the apparatus showing generally its disposition in the drill- 70 ing derrick.

Figure 2 is an elevation partly in section of one form of rotary swivel used in conjunction with the apparatus.

Figure 3 is a sectional elevation of the upper part of the hydraulic cylinder showing the preferred form of piston. 75

Figure 4 is a sectional plan through the line A—A in Figure 3.

Figure 5 is a sectional elevation of the 80 lower part of the hydraulic cylinder showing the driving bushing.

Fig. 6 is a horizontal cross-section through the cover of the hydraulic cylinder shown in Fig. 3. 85

Fig. 7 is an elevation, largely diagrammatic, showing a section of the cylinder disposed below the rotary table.

Figs. 8 and 9 are diagrammatic sectional views of the four-way valve employed for 90 controlling the operation of the feeding device.

In carrying the invention into effect according to one convenient mode, as applied by way of example to a rotary drilling apparatus in which a rotary table is driven by gearing through a chain drive from a driving sprocket combined with the drawworks, and has in the centre of the rotating part of the table, indicated by 1 in Figure 1 of the 95 100

drawings, the usual square recess 2, a special driving bushing 3a is fitted in the said table. This driving bushing forms part of a hydraulic cylinders 3 and replaces the usual 5 driving bushing by means of which rotation is imparted to the drill pipe or to the customary square drill stem connected to the pipe. The lower end of the bushing 3a is closed by means of a cover 4 bolted thereto 10 and provided with a hydraulic gland 5 containing packing 6, through which passes a hollow polished steel stem 7 having at its lower end the customary screwed connection 8 for the attachment of the drill pipe which 15 is carried down the hole to the drilling tool. The stem 7 is finished by machining or polishing to provide the least possible friction through the gland and also through the glands or parts of blow-out preventers 20 customarily used when the operations have to be carried out in the presence of considerable pressures within the well. The hydraulic cylinder 3 is formed of three sections which are bolted together as at 9 and the lower section 25 is bolted to the driving bushing 3a. A top cover 10 also bolted in position constitutes a closed cylinder.

It is to be particularly noted that the construction according to this invention provides 30 a means whereby any suitable or required length of hydraulic cylinder may be constructed to suit the operations being carried out, and it is also to be noted that if sufficient space is provided below the derrick 35 floor, one or more sections of the cylinder may be disposed below the rotary table connected to the underside of the driving bushing as shown in Fig. 7. By this means the height 40 of the hydraulic cylinder may be reduced correspondingly so as to provide a steadier drive.

The top cover 10 of the cylinder 3 is secured in place by bolts 11 and is provided with a square or splined hole 12 and a gland 13 and hydraulic packing 14 through which the top 45 driving stem 15 passes to the piston. A hold-down ring 16 is arranged on a suitably disposed shoulder 17 on the top cover 10 and a ball-bearing 18 is placed between the ring and the shoulder 17. The ring 16 carries two or 50 more eyes 19 by means of which the collar may be tied downwards or laterally to suitable anchorages in the derrick framework or base.

The hollow driving stem 15 of square or 55 splined section which passes through a corresponding square or splined hole in the top cover of the cylinder, is connected at its upper end to the stem of a rotary swivel, indicated generally at 20 in Figure 1, having the customary connection 21 for the mud or other 60 flush used in drilling which is supplied through flexible piping connections from pumps (not shown).

The rotary swivel 20 is provided with 65 means whereby the mud flush may be passed

downwardly through the hollow driving previously referred to and to the lower stem and the drill pipe, and also includes connection means whereby hydraulic operating fluid may be passed through the swivel and 70 through small pipes arranged in the square driving stem to opposite sides of the piston within the hydraulic cylinder as will be described hereinafter.

The piston 22 is provided with hydraulic 75 packing 23 fitting closely to the walls of the cylinder 3 and has a central hole 24 throughout its length. It is connected by the usual threaded means 25 to the lower end of the squared drive stem 15 and to the upper end 80 of the lower stem 7. Within the central bore of the piston are two pipe connections comprising hollow screwed bolts 26 and 27 and elbow members 28 and 29. These communicate with the lower and upper sides of the 85 piston respectively. Small pipes 30 and 31 located within the hollow driving stem are screwed into the elbows 28 and 29 and these pipes are connected at the swivel to flexible pipes 32, 33 connected in turn to fixed standpipes 34, 35 arranged at the side of the derrick. The said standpipes are supplied with hydraulic fluid under pressure from a suitable source and the flow is controlled by a four-way valve 36 having an operating 90 handle 37. A form of controlling valve is shown diagrammatically in Figs. 8 and 9, in which referring to Fig. 9 the left-hand branch may be connected to the source of fluid pressure, the right-hand branch to exhaust, the upper branch to the upper side of the piston 22 and the lower branch to the lower side thereof.

The rotary swivel 20 comprises a tubular body portion or stem 38 attached by a screwed connection to the driving stem 15 and having at its upper end a screwed casing 39 joined to an upper ring 40. Within the said casing and separate therefrom is an inner sleeve 41 which is hollow throughout its length and has an integral collar 42 providing a seat for a ball bearing 43 which is interposed between the upper face of the collar 42 and an internal shoulder 44 of the upper ring 40. The upper end of the inner sleeve is connected by a screwed joint 45 to a collar 46 which forms a flange and is attached by means of bolts 47 to a goose-neck having a connection 21 for the admission of mud or other flush. The lower end of the sleeve 41 is connected by means of a screwed joint 50 to a wash-pipe 51 which passes downward through a gland 52 screwed into the body of the swivel and provided with packing 53. The gland is secured by a locking ring 54. Mud flush is thus permitted to flow from the connection 21 to the bore of the swivel body and thence to the hollow drive stem through the screwed connection, while at the same time rotation of the body of the swivel with 120 110 115 120 125 130

respect to the inner sleeve 41 and the goose-neck 48 is also permitted.

The top ring 40 of the swivel is adapted to receive a screwed collar 55 forming a lower bearing for the inner sleeve 41 and is held in position by a locking ring 56, thus maintaining the sleeve in position vertically.

Fitted in the top of the goose-neck 48 and rotatable therein is a manifold 57 of circular cross-section having two longitudinal passages 58, 59 which are screwed to the two small pipes 30 and 31 communicating respectively with the upper and lower sides of the hydraulic piston 22. The manifold is provided with a hydraulic gland 60 and packing 61 which prevents ingress or egress of pressure fluid. The top of the goose-neck 48 is provided with a flange 62 to which is bolted a cover 63 arranged to enclose within it an annular space surrounding the upper end of the manifold. The latter has a reduced upper end 64 containing an extension of the passage 58 which projects through a central opening in the cover 63 and communicates with an upper goose-neck 65 provided with a pipe connection 66 for the supply of pressure fluid. The upper end of the manifold 64 is surrounded by packing 67 and the upper goose-neck 65 is provided with a gland 68 and packing 69. The annular space inside the cover 63 communicates with the passage 59 in the manifold and is also provided with a pipe connection 69 for the supply (or discharge) of pressure fluid. The goose-neck 65 is bolted to an upper flange 70 of the cover 63.

By the means described above the pressure fluid from pumps or some other suitable source may be admitted to or discharged from either side of the piston of the hydraulic cylinder. Suitable valves may be fitted both to the cover 63 or to the upper goose-neck 65 for releasing trapped air, and threaded connections for this purpose are provided at 71 and 72.

A pressure gauge 73 is fitted to the stand-pipe 35 which carries the hydraulic controlling fluid to or from the annular space below the piston in the hydraulic cylinder. This gauge is suitably calibrated to indicate the total weight suspended on the upper stem of the drill string by means of the pressure in the controlling fluid below the piston, and by inference the actual pressure which is being applied to the cutting edges of the tools at the foot of the well may be ascertained.

In operating the apparatus the rotary swivel is suspended by the customary hoisting apparatus in the derrick by means of which it may be hoisted or lowered at will, together with the drilling equipment attached thereto. During the operation of drilling, however, it will be free from suspension by the said apparatus, but may be steadied in its vertical movement by means

of suitable guys attached to the structure of the derrick.

The drill pipe and tools having been set in the usual manner in the hole and connected to the lower end of the hollow stem 7 which passes into the hydraulic cylinder 3, as previously described, the apparatus is placed in position in the rotary table 1 with usual mud flush pipe connected to the goose-neck 21 of the swivel and the hydraulic fluid supply pipes connected to their appropriate receiving means at the top of the swivel, the piston being near the top end of the hydraulic cylinder. The weight of the drill pipe is then transferred from the hoisting 70 tackle to the fluid below the piston, after which the operator may, by means of the four-way controlling valve 36, allow gradual egress of the controlling fluid from below the piston so that the drill pipe and tools move slowly downwards as the drilling progresses, the valve being set so that a predetermined and regular pressure is maintained on the gauge. When drilling has progressed to such an extent that the piston has reached the lower end of its stroke, it is again raised to the top by admitting pressure fluid below it and the apparatus is then removed from the rotary table, after which an additional drill pipe is added to the string in the hole 85 and the operation repeated.

In the event of its being desired to supplement gravity by applying downward pressure to the drill pipe in the hole, the cylinder 3 is first held down by means of guys tied to the eyes 19 of the hold-down ring 16 and attached to some convenient point on the derrick framework. By suitably controlling the admission of hydraulic fluid to the top of the piston the operator is then enabled to apply a variable downward pressure on the stem and to the drill pipe.

It will be understood that various modifications may be made in the construction and arrangement of the various parts of the apparatus described above in order to suit the variable conditions and requirements of practical working.

Having now described my invention, what I claim as new and desire to secure by Letters Patent is:—

1. A rotary well drilling apparatus of the class described comprising a rotary table for driving a drill stem movably arranged therein, a fluid pressure feeding device for the drill removably fitted to the rotary table and means for supplying pressure fluid to said device through the drill stem.

2. A rotary well drilling apparatus of the class described comprising a rotary table for driving a drill stem movably arranged therein, a fluid pressure feeding device for the drill having a cylinder removably fitted to the rotary table and a piston associated with the drill stem, and means for supplying pres- 130

- sure fluid to said device through the drill stem.
3. A rotary well drilling apparatus of the class described comprising a rotary table for driving a drill stem movably arranged therein, a fluid pressure feeding device for the drill having a cylinder formed and adapted to be received and driven by a rotary table of normal construction and a piston operatively associated with the drill stem, and means for supplying pressure fluid to said device through the drill stem. 70
4. A rotary well drilling apparatus of the class described comprising a rotary table for driving a drill stem movably arranged therein, a driving bushing adapted to be received and driven by said rotary table, a fluid pressure feeding device for the drill having a cylinder in driving connection with said bushing and a piston operatively associated with the drill stem, means forming a driving connection between said cylinder and the drill stem and means for supplying pressure fluid to said device through the drill stem. 75
5. A rotary well drilling apparatus of the class described comprising a rotary table for driving a drill stem movably arranged therein and a fluid pressure feeding device for the drill comprising a piston mounted on the drill stem, a cylinder cooperating with said piston and removably associated with the rotary table and means for supplying pressure fluid to said cylinder through the drill stem. 80
6. A rotary well drilling apparatus of the class described comprising a rotary table for driving a drill stem movably arranged therein and a fluid pressure feeding device for the drill comprising a piston forming part of the drill stem, a cylinder cooperating with said piston and in driving association with the rotary table, means affording a driving connection between said cylinder and the drill stem and means for supplying pressure fluid to said cylinder through the drill stem. 85
7. In a rotary well drilling apparatus of the class described having a rotary table for driving a drill stem movably arranged therein, a fluid pressure feeding device for the drill comprising a piston forming a part of the drill stem and a cooperating cylinder removably mounted in the rotary table. 90
8. In a rotary well drilling apparatus of the class described having a rotary table for driving a drill stem movably arranged therein, a fluid pressure feeding device for the drill comprising a piston attached to and connecting adjacent sections of the drill stem, a cooperating cylinder removably mounted in driving association with the rotary table, means forming a driving connection between one end of the cylinder and the drill stem and gland means surrounding the stem where it leaves the said cylinder. 95
9. A feeding device for a rotary well drill- 100
- ing apparatus of the class described comprising a cylinder formed and adapted to be removably received in the standard recess of a rotary table and driven thereby, means on said cylinder for transmitting rotary motion to a drill stem passing therethrough and a piston in said cylinder adapted to form part of said drill stem. 105
10. A feeding device for a rotary well drilling apparatus of the class described comprising a cylinder having embodied in its construction a driving bushing adapted to be removably received in the standard recess of a rotary table and being provided at one end with means for transmitting rotary motion to a drill stem passing therethrough and a piston in said cylinder adapted to form part of said drill stem which is provided with means for conducting pressure fluid to and from the cylinder. 110
11. A rotary well drilling apparatus of the class described comprising a rotary table for driving a drill stem movably arranged therein, a fluid pressure feeding device for the drill having a cylinder removably seated in the rotary table and a piston operatively associated with the drill stem, means for supplying pressure fluid to the device through the drill stem whereby both upward and downward pressures may be applied to said stem, and means adapted to aid in temporarily holding down the cylinder. 115
12. A rotary well drilling apparatus of the class described comprising a rotary table for driving a drill stem passing therethrough, a fluid pressure feeding device for the drill having a cylinder removably seated in the rotary table to be driven thereby and a piston attached to and forming part of the drill stem, means on the cylinder for transmitting rotary motion therefrom to the drill stem, means for supplying pressure fluid to the cylinder through the stem whereby both upward and downward pressures may be applied to said stem, and means adapted to aid in maintaining the cylinder in seated position in the table when downward pressures are applied to the drill stem. 120
13. A feeding device for rotary well drilling apparatus of the class described comprising a cylinder formed to be removably seated in a rotary table and driven thereby, means on the end of said cylinder for transmitting rotary motion to a drill stem passing therethrough, a piston in said cylinder operatively connected to the drill stem and means on said cylinder adapted to be tied or guyed to surrounding structure to hold the cylinder seated in the table while permitting rotation of the cylinder. 125
14. A feeding device for rotary well drilling apparatus of the class described comprising a cylinder having means adapted to be removably seated in the standard recess of a rotary table and driven thereby, means on 130

the end of said cylinder for transmitting rotary motion to a drill stem passing therethrough, a piston in said cylinder operatively connected to the drill stem and a member 5 rotatably mounted on said cylinder, said member having eyes for the attachment of guy ropes thereto.

15. A rotary well drilling apparatus of the class described comprising a rotary table for 10 driving a drill stem, a fluid pressure feeding device for the drill having a cylinder removably seated in the rotary table and a piston operatively associated with the drill stem, and means for supplying pressure fluid 15 to said device through the drill stem, said cylinder being formed of a plurality of sections whereby its length may be varied as desired and certain sections may be disposed below the rotary table.

20. 16. A feeding device for rotary well drilling apparatus of the class described comprising a cylinder adapted to be removably seated in a rotary table and driven thereby, means on the said cylinder for transmitting 25 rotary motion to a drill stem passing therethrough, a piston in said cylinder operatively connected to the drill stem, and means for supplying pressure fluid to the cylinder through the drill stem, said cylinder being 30 formed in sections, certain of which may, if desired, extend below the rotary table.

17. A rotary drilling apparatus of the class described comprising a hydraulic cylinder, a driving bushing connected to said cylinder 35 and adapted to be seated in the usual recess of a rotary table, a piston in said cylinder connected at its upper end to a square or splined driving stem arranged to slide in and be driven by a correspondingly shaped 40 cover fixed to the cylinder, said piston being also connected at its lower end to a lower stem of circular section passing downwards through a gland in the lower cover of the 45 hydraulic cylinder and adapted to be connected in the usual way to the drill pipe and tools.

18. A rotary drilling apparatus of the class described comprising a hydraulic cylinder, a driving bushing connected to said cylinder 50 and adapted to be seated in the usual recess of a rotary table, a piston in said cylinder connected at its upper end to a hollow square or splined driving stem arranged to slide in and be driven by a correspondingly shaped 55 cover fixed to the upper end of the cylinder, said piston being also connected at its lower end to a hollow lower stem of circular cross section passing downwards through a gland 60 in the lower cover of the hydraulic cylinder and adapted to be connected in the usual way to the drill pipe and tools and means including a rotary swivel for passing mud flush 65 through the hollow stems and drill pipe and also for supplying pressure fluid to the hy-

draulic cylinder for controlling the feed of the drill.

19. A rotary drilling apparatus of the class described comprising a hydraulic cylinder, a driving bushing connected to said cylinder 70 and adapted to be seated in the usual recess of a rotary table, said cylinder being formed in sections some of which may, if desired, be disposed both above and below said bushing, a piston in said cylinder connected at its upper end to a hollow square or splined driving stem arranged to slide in and be driven by a correspondingly shaped cover fixed to the upper end of the cylinder, said piston being also connected at its lower end to a hollow lower stem of circular cross section passing downwards through a gland in the lower cover of the hydraulic cylinder and adapted 80 to be connected in the usual way to the drill pipe and tools, and means for supplying pressure fluid to the cylinder through the drill stem.

20. A rotary drilling apparatus of the class described comprising a hydraulic cylinder, a driving bushing connected to said cylinder 90 and adapted to be seated in the usual recess of a rotary table, a piston in said cylinder connected at its upper end to a hollow square or splined driving stem arranged to slide in and be driven by a correspondingly shaped cover fixed to the upper end of the cylinder, said piston being also connected at its lower end to a hollow lower stem of circular cross-section passing downwards through a gland in the lower cover of the hydraulic cylinder and adapted 95 to be connected in the usual way to the drill pipe and tools, and a pressure indicator for indicating the pressure of the fluid below the piston from which the actual weight suspended by the piston may be 100 known.

In testimony whereof I have signed my name to this specification.

JAMES CUTHILL.
